UNITED STATES PATENT OFFICE.

EMANUEL DAVIS, OF BROOKLYN, NEW YORK.

DESIGN FOR A STATUETTE AND SIMILAR ARTICLE OR ORNAMENT.

52,639.

Specification for Design.

Patented Nov. 12, 1918.

Application filed May 31, 1918. Serial No. 237,648. Term of patent 7 years.

To all whom it may concern:

Be it known that I, EMANUEL DAVIS, a citizen of the United States, residing at the borough of Brooklyn, city of New York, in the county of Kings and State of New York, have invented a new, original, and ornamental Design for a Statuette and Similar Article or Ornament, of which the following is a specification, reference being had to the accompanying drawing, forming part thereof.

Fig. 2 is a side perspective view thereof.
Fig. 3 is another side perspective view thereof.

I claim:

The ornamental design for a statuette and similar article or ornament as shown.

EMANUEL DAVIS.

Witnesses:

JUDOR E. HUNT,
SIDNEY HOFFMAN.
